UNITED STATES PATENT OFFICE.

WILLIAM H. HOLMES, OF COLUMBUS, OHIO.

BICYCLE-VISE.

SPECIFICATION forming part of Letters Patent No. 594,874, dated December 7, 1897.

Application filed April 15, 1897. Serial No. 632,251. (No model.)

To all whom it may concern:

Be it known that I, WILLIAM H. HOLMES, a citizen of the United States, residing at Columbus, in the county of Franklin and State 5 of Ohio, have invented certain new and useful Improvements in Machines for Holding Bicycle-Tubing while it is being Operated Upon; and I do hereby declare the following to be a full, clear, and exact description of the 10 invention, such as will enable others skilled in the art to which it appertains to make and use the same.

The object of this invention is to provide a cheap, simple, and effective machine for use 15 in the manufacture of bicycles, and is adapted to present a vise or clamp which is supported upon a revoluble table, certain devices being employed to form a rapid and secure adjustment of the several parts.

20 The invention contemplates a construction that forms a means for rigidly supporting a bicycle-frame or part thereof in order that it may be conveniently handled during the process of filing or otherwise working upon it.

25 Having the above objects in view, the invention consists in a vise supported upon a turn-table, mechanism for opening and closing the jaws of the vise, blocks attached to the jaws and presenting surfaces of peculiar 30 construction to engage tubes of different sizes, and means for clamping the turn-table against rotation.

35 The invention further consists in the particular construction and combination of the parts which constitute the vise and facilitate its operation of engaging and disengaging the work, including other details of construction that go to make up the complete machine.

40 In the following specification I have entered into a detailed description of the construction and operation of my invention, reference being had to the accompanying drawings and to numerals thereon which designate the different parts, and what I consider to be 45 the novel features of construction are specifically set forth in the claims.

50 In the drawings forming a part of this specification, Figure 1 is a front elevation of a machine constructed in accordance with my invention. Fig. 2 is a sectional view through the vise and supporting-table therefor. Fig. 3 is a side elevation. Fig. 4 is a detail view

of the blocks which are attached to the clamping-jaws. Fig. 5 is a detail view of one of the cam-levers which are employed in securing the adjustment of the parts. 55

Referring to the drawings by numerals, 1 designates a hollow column or supporting-standard, the upper end of which is bifurcated to present the diverging arms 2 2, which support a rigid bed-plate 3, having a circular recess 4 in the upper surface thereof. This standard and bed-plate form the supporting means for the vise hereinafter described and is of a sufficient height to locate the said vise 65 at the proper elevation. Upon the bed-plate, which is supported at the upper end of the column or hollow standard, is a turn-table 5, having a circular depending portion which fits within the corresponding recess or depression in the said bed-plate, the turn-table 70 forming the base of the vise. From the base-plate 5 extends upward the stationary jaw 6 of the vise, a web or flange 7 being provided to reinforce the lower part or shank of the 75 jaw. The movable jaw 8 is pivotally connected to the turn-table, and to this end the lower end of the shank of said movable jaw is embraced by the lugs or apertured ears 9 9, that extend upward from the turn-table and 80 form the bearings for a transverse pivot-pin 10, upon which the movable jaw has a rocking movement. The jaws 6 and 8 are connected to each other by a rod 11, which passes through horizontal openings in said jaws, and 85 upon the outer end of this rod, beyond the stationary jaw, is a nut 12, held in place by a pin 13, which passes through the nut and rod. To the opposite end of the rod 11 is pivoted a lever 14, having a cam-shaped end 15, 90 which bears against the outer side of the movable jaw and acts to close the same upon the stationary jaw. In the detail view it will be seen that the cam-shaped end of the lever is preferably bifurcated to practically present 95 two cams which engage the movable jaw adjoining opposite sides thereof, the rod lying between the cams, to which it is connected by the pivot or bearing pin 16. In connection with these jaws I provide wooden blocks 17 100 for holding the work, two blocks being used which are attached to the movable and stationary jaws, respectively. Each block is preferably circular, as shown in the drawings,

and is provided with a series of transverse recesses 18, which are at right angles with each other and are of different sizes, the recesses in the blocks being properly arranged 5 so as to register when the blocks are brought together and present transverse openings circular in cross-section. The blocks are also provided with axial openings 19, which are countersunk at the inner side of the block, 10 and said openings receive thimbles 20, which encircle the connecting-rod 11, and are flanged at one end to lie within the countersunk portion of the blocks. In connection with these thimbles the stationary jaws are provided 15 with set-screws 21, the inner ends of which engage the thimbles and thereby hold the blocks in fixed engagement with their respective jaws. By this arrangement or manner of connecting the blocks to the jaws they can 20 be quickly manipulated to bring the openings therein at the proper position with respect to the vise by loosening the set-screws and then turning the blocks upon their axis.

In order to secure the turn-table in an adjusted position, it is provided centrally with a depending arm 22, which passes through the bed-plate 3 and receives a cam-lever 23, similar in construction to the one which operates the movable jaw, the said cam-lever 25 30 35 bearing against the under side of the bed-plate between the arms 22 of the supporting standard.

From the foregoing description, in connection with the accompanying drawings, the 35 construction and operation of my improved machine for holding the tubes of bicycle-frames will be readily apparent, for the blocks are movable to bring any one of the openings therein at the proper position, after which the 40 lever 14 is manipulated to separate the jaws of the vise and is then pressed downward to clamp the tube between said blocks. The turn-table can then be adjusted by properly operating the lever 23 to release and then 45 clamp the same. When thus arranged, the machine is adjusted to firmly hold the tubing, which may be filed or otherwise worked upon.

For convenience the turn-table 5 is provided at one side with a shelf or ledge 24, forming the support or table to receive the tools or implements being used by the workmen in operating upon the tubing.

It will be seen from the foregoing that I 55 have provided a machine that will be of great convenience to a workman or operator in working upon bicycle-tubing, and the parts of the device are constructed and arranged with a view to provide for a quick and convenient adjustment and also present a rigid and strong structure that will not give in use.

Having thus described my invention, what I claim as new, and desire to secure by Letters Patent, is—

65 1. In a machine for the purpose set forth, the combination with the standard or support having a bed-plate at its upper end, of a turn-

table mounted upon the bed-plate and having a depending arm or member extending therethrough, a cam-lever mounted upon the 70 lower end of the arm and adapted to clamp the turn-table in an adjusted position, together with a vise supported upon the turn-table and presenting a stationary jaw, a pivoted jaw, and means for moving the pivoted 75 jaw to and from the stationary jaw, substantially as described.

2. In a machine of the character described, of the standard having a bed-plate at its upper end, a turn-table mounted on the bed-plate and having a depending arm or member which extends through the said bed-plate, and a cam-lever mounted upon the lower end of the arm or member to engage the under side of the bed-plate and clamp the turn-table in an adjusted position; together with a vise mounted upon the turn-table and consisting of a stationary jaw, a movable jaw pivoted at its lower end to the turn-table, a rod or shaft extending through the jaws and 80 having a nut or stop which bears against the outer side of the stationary jaw, and a cam-lever pivoted to the other end of the rod and bearing against the movable jaw, substantially as shown and for the purpose set forth. 85 90 95

3. In a machine of the character described, the combination with the standard or support presenting a bed-plate at its upper end, of a turn-table mounted upon the bed-plate, and means for securing the turn-table in an adjusted position upon the bed-plate; together with a vise mounted upon the turn-table and consisting of a stationary jaw, a movable jaw pivoted at its lower end to the bed-plate, a rod or shaft passed through the jaws and 100 engaging the stationary jaw, a cam-lever upon the opposite end of the rod to bear against the pivoted jaw, and wooden blocks located between the jaws and presenting recesses which receive the tubes or work to be operated upon, substantially as shown and for the purpose set forth. 105 110 115

4. In a machine of the character described, the combination with the revoluble table, and means for holding the same in an adjusted 115 position, of a vise located thereon and comprising a stationary member and a pivoted member, a rod or shaft passed through the jaws of the vise, and held in engagement with the stationary jaw, and a cam-lever pivoted 120 to the other end of the rod or shaft to bear against the pivoted jaw of the vise; together with blocks having axial openings which are countersunk at their inner ends, thimbles located in said openings to encircle the shaft, 125 and set-screws carried by the jaws to engage the thimbles and hold the blocks upon the jaws, the said blocks having recesses which register to receive the tubes or work to be operated upon, substantially as shown and 130 for the purpose set forth.

5. In a machine of the character described, the combination with a turn-table suitably supported and provided with means for hold-

ing the same in an adjusted position, of a vise mounted upon the turn-table and consisting of a stationary jaw, a pivoted jaw, a rod passed through the jaws and in positive engagement with the stationary jaw, a cam-lever pivoted to the rod and bifurcated to present double cams which bear against the outer side of the pivoted jaw at opposite edges thereof; together with blocks mounted upon the rod and having transverse recesses in their opposing faces to receive the tube or

work to be operated upon, the turn-table having a shelf or ledge, substantially as shown and for the purpose set forth.

In testimony whereof I have signed this ¹⁵ specification in the presence of two subscribing witnesses.

WILLIAM H. HOLMES.
